Primary Examiner — Karen E Eldridge Powers*Assistant Examiner* — Jasmine Mlinarcik(74) *Attorney, Agent, or Firm* — Arnold & Porter LLP(57) **CLAIM**

The ornamental design for a garment top with a control layer, as shown and described.

DESCRIPTION

FIG. 1 is a front elevational view of a garment top with a control layer;

FIG. 2 is a rear elevational view thereof;

FIG. 3 is a right side elevational view thereof;

FIG. 4 is a left side elevational view thereof;

FIG. 5 is a top elevational view thereof;

FIG. 6 is a bottom elevational view thereof;

FIG. 7 is a front elevational view of a garment top with a control layer, wherein the top has been turned inside-out;

FIG. 8 is a rear elevational view thereof;

FIG. 9 is a right side elevational view thereof;

FIG. 10 is a left side elevational view thereof;

FIG. 11 is a top elevational view thereof; and,

FIG. 12 is a bottom elevational view thereof.

The garment top shown in broken lines is environmental subject matter that forms no part of the claimed design.

1 Claim, 10 Drawing Sheets(56)
